DESIGN FOR A COIN BANK OR SIMILAR ARTICLE

Sara L. Seymour, Altadena, Calif.

Application April 8, 1946, Serial No. 128,386

Term of patent 3½ years

(Cl. D34—11)

To all whom it may concern:

Be it known that I, Sara L. Seymour, a citizen of the United States, residing at 1216 Boston, Altadena, in the county of Los Angeles and State of California, have invented a new, original, and ornamental Design for a Coin Bank or Similar Article, of which the following is a specification, reference being had to the accompanying drawing, forming a part thereof.

Figure 1 is a rear plan view of a coin bank or similar article showing my design;

Figure 3 is a perspective view of the coin bank or similar article; and

Figure 4 shows the coin bank or similar article as it appears when viewed from the front.

I claim:

The ornamental design for a coin bank or similar article, substantially as shown.

SARA L. SEYMOUR.
